WOVEN TEXTILE FABRIC

Sergei Bogdanovich, Carmel, N. Y., assignor to Weil & Durré, Inc., New York, N. Y., a corporation of New York

Application April 21, 1952, Serial No. 19,425

Term of patent 7 years

(Cl. D92—1)

To all whom it may concern:

Be it known that I, Sergei Bogdanovich, a citizen of the United States, residing at Carmel, in the county of Putnam and State of New York, have invented a new, original, and ornamental Design for a Woven Textile Fabric, of which the following is a specification, reference being had to the accompanying drawing, forming part thereof.

In the drawing the figure is a face view of a woven textile fabric, showing my new design. The full width of the fabric is disclosed horizontally and the design unit is repeated vertically in proper relation to complete the fabric.

I claim:

The ornamental design for a woven textile fabric, as shown and described.

SERGEI BOGDANOVICH.
